SLUG CASTING MACHINE

Frank C. Frolander, Elizabeth, N. J., assignor to
 Mergenthaler Linotype Company, a corpora-
 tion of New York

Application March 18, 1936, Serial No. 69,490

20 Claims. (Cl. 199—51)

This invention relates to slug casting machines of the general organization disclosed in U. S. Patent No. 436,532 to O. Mergenthaler, wherein circulating matrices and expansible spacebands are composed in line, the composed line presented to a slotted mold where it is positioned between a pair of line clamping jaws, the line justified by effecting the expansion of the spacebands to fill out the space between the line clamping jaws which determine the length of the justified line, the mold advanced into contact with the line, and filled with molten metal to form a slug or "linotype" against the matrices which produce the type characters thereon, and the matrices and spacebands thereafter separated and returned by a distributing mechanism to the magazines from which they started.

More particularly, the present improvements deal with devices for varying the expansion of the spacebands according to the varying conditions encountered in practice. When casting from lines of full length, if they are properly composed and contain their full or usual complement of spacebands, the drive of the justification bar is usually such as properly to overcome the frictional resistance offered by the spacebands and by the spreading of the line and to expand the line to the extent necessary correctly to space the words in the line. For short lines, however, say 10 or 12 ems in length, consisting of perhaps two words with one intermediate spaceband, or three words with two intermediate spacebands, the drive of the justification bar is excessive as compared with the frictional resistance offered by the spacebands and the line, with the result that the spacebands are forced to their maximum height, thus producing excessive spacing between the words which is especially noticeable on small matter. The same excessive spacing between words will also occur even with lines of full length if such lines are composed too "loose", because in that event the resistance offered by the spacebands, irrespective of the number contained in the line, will not manifest itself until all the looseness in the line has been taken up by the expansion of the spacebands.

To obviate the foregoing and other difficulties (referring now to an exemplary embodiment of the invention), there is associated with the rods that support the justification bar an adjustable cross head which acts by banking against a fixed part of the machine to limit the upward movement of the justification bar, and thus controls or limits the degree to which the spacebands may

be expanded. In this way, proper spacing between the words is effected.

For properly composed lines of matrices of a given point size, the spacing between words should be approximately the same, but as printed lines vary in the point size of the letters of which they are composed, proper typography demands that the spacing between the words vary accordingly. For this reason, the cross head which acts to limit the upward movement of the justification bar is made adjustable in accordance with the point size of the slug to be cast.

In the embodiment of the invention disclosed, the adjustment of the cross head can be made either manually, or automatically under the control of the adjustable right hand trimming knife, which latter as is well known is settable in different positions to accommodate slugs of different point sizes.

The invention is applicable to machines equipped with quadding and centering devices or without them. In either case, the expansion of the spacebands may be varied to accord with the point size of the slug to be cast from the composed line, which is a characteristic feature of the invention. Ordinarily, the automatic control of the justifying devices will answer all requirements, but in special instances, when this is not true, the manual control may be resorted to. In quadding or centering, the invention has added utility and especially when the line clamping jaws are free to move outwardly during justification of the composed line.

Referring to the drawings:

Fig. 1 is a front elevation of a portion of a "Linotype" machine equipped with the present improvements, and showing the parts set for allowing a minimum degree of expansion in the spacebands;

Fig. 2 is a front elevation of a portion of the machine shown in Fig. 1, and showing the parts set for allowing a maximum degree of expansion in the spacebands and with the cross head disengaged from the justification rods;

Fig. 3 is a front elevation, partly in section, of the cross head and showing it in locking engagement with the justification rods;

Fig. 4 is a plan view of the parts shown in Fig. 2;

Fig. 5 is a horizontal sectional view through the cross head showing the latter in locking engagement with the justification rods;

Fig. 6 is a sectional view similar to Fig. 5 but showing the cross head disengaged from the justification rods;

Fig. 7 is a vertical sectional view on line 7—7 of Fig. 1; and

Fig. 8 is a right end view of the parts shown in Fig. 1.

As is well known in machines of this character, the matrices and expansible spacebands are composed in line in an assembler and the composed line transferred to a transporter or so-called, "first elevator" which descends to present the line between a pair of clamping jaws and in front of a slotted mold, the latter by a one-quarter rotation of a mold disc or carrier having been previously located in a horizontal or casting position. Justification of the line then takes place, i. e. the long wedge portions of the spacebands are forced upwardly through the line causing it to fill out the distance between the line clamping jaws, and this is effected by the upward movement of a so-called justification bar A (Fig. 1) carried at the top of two spaced vertical rods A¹ and A² and which engages the long wedge portions of the spacebands at the bottom. Justification takes place in two stages, and the matrices are properly aligned with the mold between stages, in well known manner. During the first stage of justification, the justification bar moves up at an angle so that the spacebands at the right of the line are expanded in greater degree than those at the left. During the second stage, the bar A is driven up in a horizontal position, the spacebands at the left being acted upon first (since these now extend below those at the right), but all of the spacebands at the completion of justification have the same degree of expansion. In order to accommodate this variable movement of the justification bar A, the vertical rods A¹ and A², through which the drive thereto is imparted, are operated independently through cam controlled spring operated levers A³ and A⁴ (Fig. 1) all in well known manner.

Coming now to the present invention, there is mounted on the justification rods A¹ and A² (see Figs. 1, 2 and 3) a cross head B settable in different positions of adjustment along said rods depending upon the degree of expansion desired in the spacebands. The cross head B is equipped with a pair of banking screws b threaded into the top and at the opposite ends thereof, and which bank against a fixed cross piece C on the vise frame C¹ as the rods A¹, A² move upwardly during justification. In this manner, the uppermost position of the justification bar A is positively determined and consequently the degree to which the spacebands will be allowed to expand. To insure proper cooperation between the cross bar C and the banking screws b, the latter are adjustable and are locked in their positions of adjustment by locking nuts b¹ (see Fig. 3).

The cross head B (see Figs. 3, 4 and 5) is formed with a main body portion B¹ extending between the justification rods A¹ and A² and is provided at its right end with a sleeve portion B² encircling the rod A¹ and at its left end with a bifurcated sleeve portion B³ that partly encircles the rod A². When adjusted in any of its different positions, the cross head is locked to the rods A¹ and A² by a pair of toothed blocks B⁴ and B⁵ arranged to engage correspondingly toothed bars A³ and A⁴ mounted in recesses formed in said rods A¹ and A². The toothed bars A³ and A⁴ are sufficiently long to accommodate the full range of adjustment of the cross head B.

The toothed locking blocks B⁴ and B⁵ (see Fig. 3) are adapted to be moved into and out of engagement with their respective toothed rods A³ and A⁴ simultaneously, and to this end they are

connected with a rocking plate B⁶, pivotally mounted on the cross head B and located adjacent the center thereof in a recess provided for the purpose. The block B⁴ is formed at the right end of a slide B⁷, arranged in a recess in the body portion B¹, and which at its opposite end is pivotally connected in a loose fashion to the rocking plate B⁶ at a point above the center. The block B⁵, on the other hand, is connected (in a manner and for a purpose hereinafter mentioned) to the left end of a second slide B⁸ which is mounted in the body portion B¹ in a manner similar to the slide B⁷ and is connected at its opposite end in like manner to the rocking plate B⁶ but at a point below the center thereof. The arrangement is such that as the slide B⁷ is moved to the left, the slide B⁸ will be moved toward the right, thereby simultaneously disengaging the locking blocks B⁴ and B⁵ from the rods A² and A¹. Likewise, when the slide B⁷ is returned to the right, the slide B⁸ will be returned to the left, thus effecting the locking engagement of the blocks B⁴ and B⁵ with the rods A¹ and A² simultaneously. Normally, the blocks are held in locking engagement with their respective rods by a spring B⁹ housed in a recess B¹⁰ formed in an inclined boss at the top of the cross head and pressing against the enlarged head of a pin B¹¹ that extends through the boss at the base of the recess B¹⁰ and which banks against the slide B⁷ at the end thereof adjacent the rocking plate. The spring B⁹ is held in the recess by a screw B¹² threaded into the boss and which serves also to adjust the force exerted by the spring on the pin B¹¹.

It will be recalled that the justification rods A¹ and A² have a variable movement upward during justification for reasons hereinbefore mentioned, and as the cross head B moves as a unit with the right hand rod A¹ by virtue of the fact that the locking block B⁴ associated therewith is formed integral with the slide B⁷, provision is made to accommodate such variable movement of the rod A². To this end, the locking block B⁵ is arranged for limited vertical movement with respect to its actuating slide B⁸, the connection between the two members for this purpose being in the form of tongue and groove interengaging devices B¹³ (see Figs. 5 and 6).

The block B⁵ in the normal position of the parts (see Fig. 3) banks at its bottom against the upper end of a banking screw b² threaded into a lug b³ formed at the bottom of the cross head B, being held in such position by a compression spring b⁴ seated in a recess b⁵ formed in the cross head B above the block and pressing at its lower end against said block where it enters a shallow recess b⁶ that serves to anchor the spring properly in position at this point. Now, as the rod A² moves upwardly at a varying rate with respect to the cross head B, the block B⁵ will move along with it (against the action of the spring b⁴) until it banks against an overlying banking surface b⁷ presented by the cross head B, thus causing the arrest of the block B⁵ and consequently the rod A². In this way, the arrest of cross head B will determine the height to which the justification bar A will ascend, since the rod A¹ which determines the position of the right end of the bar A is locked to the cross head, while the rod A² which determines the position of the left end of the bar A is arrested in its ascent by the cross head itself.

The amount by which the spacebands are allowed to expand is controlled by adjusting the cross head B to different positions up and down 75

the rods A¹ and A². Before this can be done, however, the cross head must be disengaged from the rods A¹ and A² and this as previously stated is effected by actuating the slides B⁷ and B⁸ against the tension of the spring B⁹. The slide B⁷ is moved to the left or its unlocking position through the medium of a horizontal slide D (Figs. 2, 4, 5 and 6) resting in a groove formed in the sleeve B² at the front, and having at one end, 5 a thickened portion D¹ extending through a slot B¹³ in the body portion of the cross head, where the slide D is secured to the slide B⁷. At its opposite end, the slide D is equipped with a roller D² which is acted upon by a cam E pivotally mounted on a vertical axis in a bracket C² secured to the vise frame C¹. It will be noted that the active surface of the cam E is sufficiently long in a vertical direction to remain in contact with the roller D² throughout the entire range of movement 10 of the cross head B either during adjustment or operation of the latter. The normal position of cam E, i. e., when the blocks B⁴ and B⁵ are in locking engagement with the rods A¹ and A², is shown in Fig. 5, but when it is desired to 15 effect disengagement of the blocks from their respective rods, the cam E is turned in a clockwise direction, looking at the parts from the top (see Fig. 6), to bring a high portion of the cam opposite the roller D², and when this occurs the 20 slide D will be actuated to the left with the results hereinbefore set forth.

The cam E is turned in a clockwise direction through the medium of a horizontal reciprocable rod F, slidably arranged in the vise frame and 25 adapted when moved to the left to engage the cam in a notch provided for the purpose. The rod F is moved positively to the left to effect the disengagement of the cross head from the rods A¹ and A², either manually, or automatically 30 under the control of the means for adjusting the trimming knives, but is returned after the adjustment of the cross head by the spring B⁹, through the agency of the intermediate slides B⁷ and D and the cam E.

The manual adjustment of the reciprocable rod F (best illustrated in Figs. 2, 6, 7 and 8) is effected 35 by a lever G located at the right of the vise frame, beneath the knife adjusting devices, and pivoted on a pin G¹ carried by an extension c of the bracket C². The lever G at the left of the pivot is formed with a cam shaped arm G² adapted to 40 engage a roll F¹ rotatably mounted in a yoke F² formed at the right end of the horizontal rod F. As the lever is turned in a counterclockwise direction (Fig. 2), the arm G² thereof will bear against 45 the roll F¹ and force the rod F to the left, with the consequent disengagement of the cross head B from the rods A¹ and A² in the manner previously described.

When the parts have been disengaged, the cross head is free to be adjusted along the rods A¹ and A² and for this purpose another lever G³ is provided likewise pivoted on the pin G¹. The lever G³ has a long arm G⁴ extending to the left 50 and formed with a bifurcated portion G⁵ straddling a pin B¹⁴ mounted in a lug B¹⁵ formed on the sleeve B² of the cross head B (Figs. 2, 3, 5, and 6). According to this arrangement, the movement of the lever G³ in a clockwise direction 55 (Fig. 2) will raise the cross head, while movement in the opposite direction will lower it. Both the levers G and G³ are equipped with finger pieces g and g¹, respectively, which lie one directly above the other so that both may readily 60 be operated by one hand in making the adjust-

ments just alluded to. Of course, as soon as the cross head has been adjusted to the desired position, the release of the lever G will allow the cross head and rods A¹ and A² again to enter into locking engagement.

The position of adjustment of the cross head B is indicated on a scale H mounted at the front end of a fore-and-aft extension C³ of the bracket C² (see Figs. 1, 2 and 8), by a pointer g² carried on an arm G⁶ that extends forwardly from the hub of the adjusting lever G³. The scale H is graduated from 0 to 10 giving a suitable range of adjustment for matrices ranging in size from 5 to 14 points, since above 14 points the spacing between words is usually constant. However, 10 the scale is merely arbitrary and any other could be adopted if desired. The zero position of adjustment is fixed by the banking of the arm G⁴ of the lever G³ in its topmost position against a stop C⁴ projecting rearwardly from the bracket 15 C², and in this way a certain amount of space-band expansion is insured even for matrices of the smallest point sizes.

Provision has been made whereby all the above 20 adjustments may be carried out automatically, 25 and in the exemplary embodiment shown the mechanism for adjusting the right hand trimming knife has been utilized for the purpose. In the commercial "Linotype" machine, the right 30 hand trimming knife (see Figs. 2, 4 and 7) is carried by a block J slidably arranged in a bracket J¹ secured to the vise frame. The block J and consequently the knife is urged under spring tension away from the left hand knife, and its position is determined by one or another of a series 35 of banking studs J² of different lengths carried by a disc adjustable through the medium of a knob J³ (Figs. 1 and 4). In order to effect the adjustment of the knife block, the knob J³ must first be pulled out toward the right before the 40 different banking studs can be brought into registry with the knife block. The construction of the knife adjusting mechanism is more fully disclosed in U. S. Patent No. 1,656,639, dated January 17, 1928, if further details thereof are 45 desired.

This outward movement of the knob J³ and the 50 different adjustments of the knife block J have been utilized in the automatic setting of the cross 55 head B. A number of the parts used in the automatic setting of the cross head are common to the devices for manually setting the parts; those that are not are all carried by a bracket or casting K mounted on the knife block support J¹ by means of four set screws k, k¹, k² and k³, two extending inwardly, one from the front and the other from the rear portions of the bracket and banking against a portion of the knife block support, and the others extending one downwardly and one upwardly and banking 60 against another portion of the knife block support (see Fig. 7).

As the knob J³ is pulled outwardly prior to the adjustment of the knife block, a collar J⁴ thereon (see Figs. 2 and 8) engages the upper end of a lever K¹ pivotally mounted adjacent its center and at an angle with the vertical, in an offset portion K² of the bracket K, causing the lower end of said lever to be moved to the left in the direction of the vise frame. The lever K¹ at its 65 lower end is pivotally connected to a rod K³ slidably supported in two depending lugs k⁴ and k⁵ of the bracket K. By reason of this connection, the rod K³ likewise is moved to the left under the influence of the lever K¹ and this movement, 70 75

through a rigid offset connection K^4 , is transmitted to a second rod K^5 which acts on the yoke piece F^2 to move the cam actuating rod F to the left. This action of the rod F , it will be recalled, effects the disengagement of the cross head from the justification rods A^1 and A^2 and it performs the same function in the automatic setting of the parts.

When the knob J^3 has been withdrawn, it is turned in one direction or another to set the knife block J , and the setting of the latter in turn effects the setting of the cross head with respect to the justification rods. This setting is brought about through the medium of a stud K^6 projecting forwardly from the knife block J (see Fig. 7) through a slot K^7 formed in the knife block support, and which acts on the upper end of a lever K^8 pivotally mounted at a point somewhat above its center on an upstanding portion K^9 of the bracket K . The lower portion of the lever K^8 is bent and rebent to clear a portion of the bracket K , and is pivotally connected at its lower end, by means of a retractible pin K^{10} , with the arm G^6 of the adjusting lever G^3 . According to this arrangement, as the knife block moves to the left to effect a closer spacing of the knives for slugs of smaller point size, the stud K^6 will turn the lever K^8 in a counterclockwise direction (Fig. 2), and it in turn will move the lever G^3 in a clockwise direction to raise the cross head, the lever G^3 acting in the same manner as it does when the parts are manually adjusted.

When the knife block is moved outwardly to set the knives to accommodate slugs of larger point sizes, the lever K^8 will move in a clockwise direction under the influence of a tension spring K^{11} fastened to said lever near the lower end thereof, and anchored in the bracket K . This movement of the lever K^8 will turn the lever G^3 in a counterclockwise direction to lower the cross head B , which of course is the way said lever acts when the parts are manually adjusted. The parts are so proportioned that a change in setting of the knives from one point size to another, will effect a change in the setting of the cross head B corresponding to that which would occur if the parts were manually set for an equivalent change in point size. After the knives have been adjusted and consequently the position of the cross head B , the knob J^3 will be returned to its inner normal position and this in turn will allow the locking engagement between the cross head and the rods A^1 and A^2 to be restored.

It will be recalled that in the present arrangement, the range of adjustability of the cross head has been confined to those cases wherein the size of the characters range between 5 and 14 points for reasons heretofore given, and the same limitations have been placed upon the mechanism when the parts are automatically set. Thus as shown in Fig. 2, when the right hand knife has been set to accommodate a slug larger than 14 points, the movement of the lever K^8 in a clockwise direction is arrested by a stud K^{12} threaded into the bracket K and against which the lever K^8 banks, and in this way the lowermost position of the cross head B is determined and consequently the maximum degree of expansion of which the spacebands can partake for this setting of the parts.

If it is desired to cut out the automatic adjustment of the parts, this may be readily done by withdrawing the pin K^{10} from the arm G^6 of the lever G^3 and also the pivot pin by which the lever K^1 that controls the locking and unlocking devices is held in the bracket arm K^2 (see Fig. 8).

Although in describing the present improvements their chief application has been cited in connection with lines of short length, it is apparent that they act quite independently of the length of the line and can be used whenever it is desired to maintain uniform spacing of the words throughout a series of lines, even when the latter are of full length. 5

In the accompanying drawings, the invention has been shown merely by way of example and in preferred form, and obviously, many variations and modifications may be made therein which will still be comprised within its spirit. It is to be understood, therefore, that the invention is not limited to any specific form or embodiment, except insofar as such limitations are specified in the appended claims. 10 15

Having thus described my invention, what I claim is:

1. A slug casting machine wherein a line of 20 matrices and expansible spacebands is adapted to be presented in line justifying position prior to casting and including, in combination, justifying devices movable to expand the spacebands in the line and comprising a justification bar and two 25 independently operable justifying rods, and adjustable means mounted on the justifying devices and adapted to cooperate with a fixed portion of the machine in controlling the spaceband expanding 30 movement of both justifying rods. 30

2. A slug casting machine wherein a line of 35 matrices and expansible spacebands is adapted to be presented in line justifying position prior to casting and including, in combination, justifying devices movable to expand the spacebands in the line and comprising a justification bar and two 40 independently operable justifying rods, means mounted on the justifying devices and adapted to cooperate with a fixed portion of the machine for arresting the movement of both justifying rods, and mechanism for locating said arresting 45 means in different positions on the justifying devices in order to vary the extent of the spaceband expanding movement thereof. 50

3. A slug casting machine wherein a line of 45 matrices and expansible spacebands is adapted to be presented in line justifying position prior to casting and including, in combination, justifying devices movable to expand the spacebands in the line and comprising a justification bar and two 55 independently operable justifying rods, means normally mounted in locked engagement on the justifying devices and adapted to cooperate with a fixed portion of the machine for limiting the spaceband expanding movement of both justifying rods, and mechanism for unlocking said means 55 from the justifying devices whereby the same may be adjusted to vary the extent of the spaceband expanding movement of the justifying devices. 55

4. A slug casting machine wherein a line of 60 matrices and expansible spacebands is adapted to be presented in line justifying position prior to casting and including, in combination, justifying devices movable to expand the spacebands in the line, and means operable independently of the 65 length of the line for controlling the extent of the spaceband expanding movement of the justifying devices. 65

5. A slug casting machine wherein a line of 70 matrices and expansible spacebands is adapted to be presented in line justifying position prior to casting and including, in combination, justifying devices movable to expand the spacebands in the line, means operable independently of the length 75 of the line for controlling the extent of the spaceband expanding movement of the justifying devices. 75

band expanding movement of the justifying devices, and mechanism for adjusting said controlling means whereby the extent of such movement may be varied as required.

5 6. A slug casting machine wherein a line of matrices and expansible spacebands is adapted to be presented in line justifying position prior to casting and including, in combination, justifying devices movable to expand the spacebands in the 10 line, means operable independently of the length of the line for controlling the extent of the spaceband expanding movement of the justifying devices, and mechanism for manually adjusting said controlling means whereby the extent of such 15 movement may be varied as required.

7. A slug casting machine wherein a line of matrices and expansible spacebands is adapted to be presented in line justifying position prior to casting and including, in combination, justifying 20 devices movable to expand the spacebands in the line, means for controlling the extent of the spaceband expanding movement of the justifying devices, and mechanism for automatically adjusting said means whereby the extent of such 25 movement may be varied as required.

8. A slug casting machine wherein a line of matrices and expansible spacebands is adapted to be presented in line justifying position prior to casting and including, in combination, justifying 30 devices movable to expand the spacebands in the line, means for controlling the extent of the spaceband expanding movement of the justifying devices, and mechanism for automatically adjusting said controlling means in accordance with the 35 point size of the slug cast from the line.

9. A slug casting machine wherein a line of matrices and expansible spacebands is adapted to be presented in line justifying position prior to casting and including, in combination, justifying 40 devices movable to expand the spacebands in the line, means operable independently of the length of the line for controlling the extent of the spaceband expanding movement of the justifying devices, and mechanism for automatically adjusting 45 said controlling means in accordance with the point size of the slug cast from the line.

10. A slug casting machine wherein a line of matrices and expansible spacebands is adapted to be presented in line justifying position prior to casting and including, in combination, justifying 50 devices movable to expand the spacebands in the line, means for controlling the extent of the spaceband expanding movement of the justifying devices, adjustable slug trimming mechanism, and 55 instrumentalities acting under the control of said slug trimming mechanism for adjusting said controlling means to vary the extent of movement of the justifying devices.

11. A slug casting machine wherein a line of 60 matrices and expansible spacebands is adapted to be presented in line justifying position prior to casting and including, in combination, justifying devices comprising a justifying bar and a pair of spaced justifying rods movable to press the justifying bar against the spacebands to effect their 65 expansion, and adjustable means mounted on said rods and adapted to cooperate with a fixed portion of the machine for varying the extent of spaceband expanding movement of the justifying 70 bar.

12. A slug casting machine wherein a line of 75 matrices and expansible spacebands is adapted to be presented in line justifying position prior to casting and including, in combination, justifying devices comprising a justifying bar and a pair of

spaced justifying rods movable to press the justifying bar against the spacebands to effect their expansion, and adjustable means mounted on said rods and adapted to cooperate with a fixed portion of the machine for varying the extent of spaceband expanding movement of the justifying bar, said adjustable means including a cross head, devices associated with the cross head normally locking it to the justifying rods, and means for unlocking said cross head to facilitate its adjustment.

13. A slug casting machine wherein a line of matrices and expansible spacebands is adapted to be presented in line justifying position prior to casting and including, in combination, justifying 15 devices comprising a justifying bar and a pair of spaced justifying rods movable relatively to press the justifying bar against the spacebands to effect their expansion, adjustable means mounted on said rods and adapted to cooperate with a fixed portion of the machine for limiting the extent of spaceband expanding movement of the justifying bar, and separate devices for locking the adjustable means to the respective justifying rods, said locking devices being relatively movable when in engagement with the justifying rods to accommodate the relative movement of the latter.

14. A slug casting machine wherein a line of matrices and expansible spacebands is adapted 30 to be presented in line justifying position prior to casting and including, in combination, justifying devices comprising a justifying bar and a pair of spaced justifying rods movable relatively to press the justifying bar against the spacebands 35 to effect their expansion, an adjustable cross head mounted on said rods and adapted to cooperate with a fixed portion of the machine for limiting the extent of spaceband expanding movement of the justifying bar, separate devices for locking 40 the cross head to the respective justifying rods, and means for disengaging said locking devices from the justifying rods to permit adjustment of the cross head with respect thereto, said locking devices being relatively movable when in engagement 45 with the justifying rods to accommodate the relative movement of the latter.

15. A slug casting machine wherein a line of matrices and expansible spacebands is adapted to be presented in line justifying position prior to 50 casting and including, in combination, justifying devices comprising a justifying bar and a pair of spaced justifying rods movable relatively to press the justifying bar against the spacebands to effect their expansion, an adjustable cross head 55 mounted on said rods and adapted to cooperate with a fixed portion of the machine for limiting the extent of spaceband expanding movement of the justifying bar, separate devices for locking the cross head to the respective justifying rods, 60 and common means for disengaging said locking devices from the justifying rods to permit adjustment of the cross head with respect thereto and for reengaging them therewith after adjustment has been made, said locking devices being relatively movable when in engagement with the justifying rods to accommodate the relative movement of the latter.

16. A slug casting machine wherein a line of matrices and expansible spacebands is adapted to 70 be presented in line justifying position prior to casting and including, in combination, justifying devices comprising a justifying bar and a pair of spaced justifying rods movable relatively to press the justifying bar against the spacebands to effect 75

- their expansion, an adjustable cross head mounted on said rods and adapted to cooperate with a fixed portion of the machine for limiting the extent of spaceband expanding movement of the 5 justifying bar, a plurality of toothed locking elements carried by the cross head arranged to engage complementary toothed means on the justifying rods for locking the cross head to said rods, and common means for disengaging the locking 10 elements from the rods to permit adjustment of the cross head, said toothed locking elements being relatively movable when in locking engagement with the rods to accommodate the relative movement of the latter.
- 15 17. A combination according to claim 16, wherein one of said locking elements has a fixed relation with the cross head when in locking engagement with its respective justifying rod, and the other locking element has a limited range of 20 movement on the cross head for accommodating the movement of the rod with which it is associated.

18. A combination according to claim 12, wherein there is provided means including a manually operable lever for effecting the disengagement of the locking devices from the justifying rods, and a second manually operable lever 5 for adjusting the cross head when the parts are thus disengaged.

19. A combination according to claim 12, including automatic means for effecting the disengagement of the locking devices from the justifying rods and for adjusting the cross head when 10 the parts are thus disengaged.

20. A combination according to claim 12, wherein the machine is equipped further with adjustable slug trimming mechanism and wherein 15 in the disengagement of the locking devices from the justifying rods and the adjustment of the cross head are effected automatically under the control of said slug trimming mechanism.

20 FRANK C. FROLANDER.
